AIR CONDITIONING APPARATUS

Lars Hanson, Syracuse, N. Y., assignor to Carrier Corporation, Syracuse, N. Y., a corporation of Delaware

Application June 4, 1938, Serial No. 211,761

2 Claims. (Cl. 62—4)

This invention relates to air conditioning, and more particularly to air conditioning apparatus including a refrigerating system of the compression type.

The general object of the invention is to provide an improved system for controlling and regulating the operation of an air conditioning apparatus including a refrigerant compressor driven by an internal combustion engine or the like.

It is an object of the invention to provide an apparatus of the type referred to which may be used to particular advantage in the conditioning of vehicles such as buses and railway cars, and which may also be used to advantage in stationary installations, as in homes or the like.

Another object of the invention is to provide a system of the type referred to in which the supply of liquid refrigerant to the evaporator of the system is permitted only when the compressor of the system is operating at a desired relatively high speed.

Another object of the invention is to provide a system of the type referred to in which provision is made for unloading the compressor during starting-up periods, so that the compressor may attain a desired relatively high speed in a short time and without difficulty before the normal operating load is imposed thereon.

A further object of the invention is to provide a system of the type referred to in which provision is made for cutting the compressor out of fluid-compressing service whenever the load thereon falls below a predetermined point, while the compressor continues to be actuated by its associated driving means.

Other objects of the invention are to provide a system of the type referred to which is controlled automatically in such manner as to insure at all times the maintenance of desired atmospheric conditions in the area served by the apparatus; which is reliable in operation; and which is relatively simple and inexpensive.

A feature of the invention resides in controlling the supply of liquid refrigerant to the evaporator of the system in accordance with the pressure in the inlet passage of the engine or the like, driving the compressor. Whenever the pressure in the inlet passage is lowered sufficiently to indicate that the engine, and hence the compressor, are operating at relatively high speed, refrigerant may be supplied to the evaporator; and, whenever the pressure in the inlet passage increases beyond a predetermined point, indicating a reduction in speed of the engine and compres-

sor, the supply of refrigerant to the evaporator is interrupted.

Another feature of the invention resides in the provision of a valve-controlled bypass line connecting the discharge side of the compressor with the suction side thereof, means for opening the normally-closed valve during the interval during which the starting switch of the system is operated, and means for opening the valve at other times during the operation of the system when the evaporator or suction pressure falls below a predetermined point. The valve in the compressor bypass line is closed whenever normal compression action is to be provided.

Other objects, features and advantages of the invention will be more apparent from the following description to be read in connection with the accompanying drawing, in which:

Fig. 1 diagrammatically represents an apparatus embodying the invention;

Fig. 2 diagrammatically represents the wiring diagram and control system utilized in conjunction with the apparatus of Fig. 1; and

Fig. 3 is a view similar to Fig. 2 illustrating a modified wiring diagram.

Referring now to the drawing, the numeral 10 represents the condenser of a refrigerating system including receiver 11, evaporator 12 and compressor 13. The compressor 13 is adapted to deliver compressed refrigerant to the condenser 10 through line 14 and the condenser discharges into receiver 11 through line 15. Liquid refrigerant supply line 16 is adapted to supply liquid refrigerant from the receiver 11 to the evaporator 12, and 17 represents the gas suction line through which refrigerant is delivered from the evaporator to the inlet connection of compressor 13. Compressor 13 is driven in any suitable manner, as through shaft 18, by an internal combustion engine or the like, designated 19. The engine 19 is provided with a customary cooling means such as radiator 20 to and from which the engine cooling medium is circulated through lines 21 and 22 respectively in well-known manner. A fan 23 is provided to circulate air over the heat exchange surfaces of the radiator 20.

The condenser 10 is preferably cooled by the circulation of air thereover and, as illustrated, a fan 24, driven by shaft 18 through belt 25 serves to circulate air through the condenser housing 26. It is to be understood, however, that the arrangement shown in the drawing is intended as illustrative only and that any suitable condenser arrangement may be employed. Similarly, the evaporator 12 is illustrated as being dis-

posed within a housing 27 through which air which is to be supplied to the conditioned enclosure is circulated by fan 28 driven by motor 29.

The invention is particularly well adapted for the conditioning of vehicles such as buses or railway cars, and in such applications the driving engine 19, compressor 13 and condenser 10 are preferably mounted beneath the floor level of the vehicle, while the evaporator and its associated fan 28 are preferably mounted within the body portion of the vehicle to be conditioned. Since various arrangements of this general type are well known in the art, no detailed description is required of the manner in which the apparatus may be mounted, or the manner in which desired air circulation and distribution may be effected.

It is to be understood that the engine 19 is provided for the principal purpose of operating the compressor, and where the invention is applied to an engine-operated vehicle, the engine 19 is distinct from and is provided in addition to the engine used for propelling such vehicle.

Considering more particularly the control apparatus, the numeral 30 designates an expansion valve of any suitable type under the control of thermal bulb or the like 31a, mounted in heat exchange relation with the suction line at the outlet end of evaporator 12. In a manner well-known in the art, the thermal bulb 31a serves to regulate the degree of opening of expansion valve 30 to provide the desired cooling effect within the evaporator 12. Valve 31, positioned in line 16, preferably between receiver 11 and expansion valve 30, is adapted to control the supply of refrigerant liquid from the receiver 11 to the expansion valve, the valve 31 preferably being of the on-and-off type. Suction line 17 is connected to compressor discharge line 14 by bypass line 32 provided with a valve 33, the valve 33 preferably being designed either to permit relatively unrestricted flow through bypass line 32 or completely to interrupt the flow of fluid through bypass line 32.

The suction manifold 34 of engine 19 is provided with a pressure-responsive element 35 adapted to respond to changes in pressure in the suction manifold which occur in accordance with changes in the operating speed of the engine 19. Thus when the engine 19 is operating at relatively low speed or not at all, the pressure in manifold 34 will be relatively high, but as the speed of engine 19 is increased the pressure in suction manifold 34 will be correspondingly decreased.

Referring more particularly to Fig. 2, the numeral 36 designates a switch panel or the like, provided with a pair of manually operable single-pole single-throw switches, designated 37 and 38 respectively. The numeral 39 designates a starter switch provided with a double pole single-throw switch designated 40.

When it is desired to place the system in operation, the switches 37 and 38 are closed and the operator then presses the starting switch 40 to close the same for a short interval. Closing the switch 37 completes a circuit including battery 41, lead 42 and motor 29, thus to place in operation the motor 29 driving fan 28 serving to circulate air over the evaporator 12. Closing of the starting switch 40 completes a circuit including battery 41, lead 42, lead 43 and solenoid 44 of starter relay 45. Lead 46 leading from the battery 41 is discontinuous and the flow of electricity therethrough is dependent upon the attraction of armature 47 to the contacts 48 by the so-

lenoid 44. When the starting switch is in closed position the armature 47 is attracted to complete an electrical circuit including lead 46 and starting motor 49, which serves to start the engine 19 in a well-known manner. The motor 49 is of such type that it is disengaged from the engine 19 when the engine has attained a predetermined speed. The energization of motor 49 is interrupted when, after a short interval, the starting switch 40 is opened by the operator. Lead 50, connecting to one of the terminals of switch 40 and to a signal device, such as lamp 51, serves to give indication of the fact that the starter switch is closed. The energization of signal switch 51 is interrupted whenever the switch 40 is in open position.

During the time that the starter switch 40 is closed, there is established an electrical circuit including lead 42, switch 40, lead 52 and solenoid 53. Solenoid 53 is adapted to control valve 33 in bypass line 32, the valve being arranged to be opened whenever the solenoid 53 is energized. Since solenoid valves of various types are well-known in the art, and since the solenoid-controlled valve 33 does not per se, form part of the present invention, no further description of this element is deemed necessary. It will thus be observed that during the starting-up interval during which starting switch 40 is closed, the valve 33 is opened. Thus, as the engine 19 begins its operation, the gas which is discharged from the compressor is recirculated back to the intake of the compressor at substantially the suction pressure. Thus, there is no effective compressing action and the compressor is completely unloaded, the only force required to drive the compressor under such conditions being that necessary to overcome friction losses. Upon opening the starting switch 40 the energization of solenoid 53 through lead 52 is interrupted. Thereafter the energization of solenoid 53 is controlled by a circuit including battery 41, lead 42, switch 37, lead 54, lead 55, lead 56 and pressure-controlled switch 57. The switch 57 is controlled by a pressure-responsive element 58 disposed in suction line 17, the arrangement being such that the switch 57 is closed whenever the pressure-responsive element 58 indicates a suction pressure lower than a predetermined point. Accordingly, whenever there is a relatively high suction pressure in the suction line 17, indicating a need for active compressing action, the switch 57 is in opened position, thus to prevent energization of solenoid 53 and thus to maintain the valve 33 in closed position.

In starting up the apparatus, the compressor is unloaded by energization of solenoid 53 through lead 52, as above explained. The operator maintains the starting switch 40 in closed position until the engine and compressor come up to speed. Thus during the starting-up period, the valve 33 is maintained in open position and the compressor is substantially completely unloaded. This continues until the engine and compressor have attained their intended relatively high speeds, after which the switch 40 is opened and normal operation of the system is established.

The valve 31 controlling the supply of refrigerant liquid from the receiver 11 to the evaporator 12 is controlled by solenoid 59 adapted to be energized by battery 41 through lead 42, switch 37, lead 54, lead 55, switch 38 and lead 60. In lead 60 is interposed a thermostatic switch 61 adapted to be closed whenever the en-

closure to be conditioned requires cooling. Since thermostatic switches of this type are well-known in the art, no detailed description of this feature is deemed required. Also disposed in the lead 60 is a pressure switch 62 which is controlled by pressure-responsive element 35 positioned in the suction manifold of the engine 19. The function of valve 31 is to prevent the supply of refrigerant liquid to the evaporator 12 until the engine 19 and compressor 13 have attained a predetermined relatively high speed and, accordingly, the solenoid 59, which is adapted to open the valve 31 when it is energized, must not be energized until the desired compressor speed has been attained. Since the pressure in suction manifold 34 drops as the speed of the engine increases, the pressure-responsive element 35 is arranged to close pressure switch 62 only after the pressure in suction manifold 34 has fallen to a predetermined point, thus to indicate that the engine and compressor have attained the desired speed. Since various types of such pressure switches are well-known in the art, no further description of this feature is deemed required here, but it is to be observed that the invention contemplates that the pressure-responsive element 35 may be disposed at any desired point in the inlet passage or passages connecting with the engine 19, or in communication with such passages, and is not restricted to any particular location of this element.

The lead 60 is preferably provided with a second pressure-controlled switch 63 under the control of pressure-responsive element 64 disposed in discharge line 14. The pressure switch 63 is normally closed but is adapted to be opened whenever the pressure in line 14 rises above a predetermined point, so as to interrupt the supply of refrigerant to the evaporator.

To provide against continued operation of the engine 19 after the switch 31 has been opened, or whenever a similar break in the circuit occurs as by burning out of fuse 29a in the circuit of fan 29, there is preferably provided a relay 65 which controls the grounding of the magneto 66 serving the engine 19. Solenoid 67 is adapted to be energized whenever switch 31 is closed, the circuit including battery 41, lead 42, switch 31, lead 54 and lead 68. When the solenoid 67 is energized, it attracts armature 69 thus to open lead 70 connecting the magneto 66 to ground. Whenever the switch 31 is open the energization of solenoid 67 is interrupted, the armature 69 completes the continuity of lead 70, grounding the magneto 66 and thus interrupting operation of the engine 19.

The circuit illustrated in Fig. 3 is essentially the same as that illustrated in Fig. 2. However, there is provided an additional lead 71 having a switch 72 and a resistance element 73. If it is desired to run the motor 29 at reduced speed, as may be desired under winter operating conditions when the fan 28 is used to circulate air over a suitable heating device, the switch 72 is closed while the switch 31 is maintained open. The insertion of resistance 73 in the circuit of motor 29 will serve to reduce the speed thereof in a manner well understood.

Fig. 3 as illustrated contains an ignition switch 74 and an ignition coil 75 rather than the magneto of Fig. 2, the ignition coil being provided with a suitable breaker 76 in a manner well understood.

In operation, whenever the thermostat con-

trolling switch 61 is satisfied, indicating that there is no need for further conditioning of the conditioned enclosure, the switch 61 is opened and the valve 31 is therefore closed. The compressor meanwhile continues to withdraw refrigerant from the evaporator 12 until the pressure in the suction line 17 is sufficiently low to cause switch 51 to close whereby valve 33 in the compressor bypass line is opened to unload the compressor 12. During the remainder of the period during which there is no demand for cooling, the compressor 13, driven by the constantly operative engine 19, continues to operate without load. Upon a demand for cooling, the switch 61 is closed and the refrigerant supply valve 31 is opened. The supply of refrigerant to the evaporator and the evaporation thereof increases the suction pressure in line 17 and this increase continues until the switch 51 is opened whereby the bypass valve 33 is closed. Normal operation is thereupon resumed as above described, this operation being controlled entirely automatically.

Since many changes may be made in the invention without departing from its scope, it is intended that all matter contained in the above description or shown in the accompanying drawing shall be interpreted as illustrative only and not in a limiting sense, applicant limiting himself only as indicated in the appended claims.

30 I claim:

1. In an apparatus of the character described including a condenser, an evaporator and a compressor driven by an internal combustion engine having a starting motor associated therewith, the combination of a compressor suction line connecting said evaporator and said compressor, a compressor discharge line connecting said compressor and said condenser, a bypass line connecting said discharge line and said suction line, 35 a normally closed valve in said bypass line, means for energizing said starting motor, means for opening said valve whenever said starting motor is energized, whereby said engine may be started up with practically no load on the compressor, and means for controlling the opening and closing of said valve during operation of said compressor and subsequent to the de-energization of said starting motor in accordance with changes in the pressure in said suction line, said 40 last-mentioned means serving to open said valve whenever said pressure falls below a predetermined point, said starting motor being adapted to be de-energized after said engine has been placed in normal operation.

55 2. In an apparatus of the character described including a condenser, an evaporator and a compressor driven by an internal combustion engine having a starting motor associated therewith, the combination of means for bypassing to the inlet 60 of said compressor fluid discharged from the discharge side of said compressor, means for rendering operative said last-mentioned means whenever said starting motor is energized, and means for rendering operative said bypass means whenever the pressure of refrigerant delivered from said evaporator falls below a predetermined point, said bypass means normally being inoperative, whereby bypassing of refrigerant discharged from said compressor to the inlet thereof is prevented except when said starting motor is energized or the pressure of refrigerant delivered from said evaporator falls below a predetermined point.

LARS HANSON.
